Application December 20, 1952, Serial No. 22,799

Term of patent 14 years

(Cl. D58—12)

To all whom it may concern:

Be it known that we, Irving M. Footlik and Frank Johnson, both citizens of the United States, residing at Chicago, in the county of Cook and State of Illinois, have invented a new, original, and ornamental Design for a Tote Box, of which the following is a specification, reference being had to the accompanying drawing, forming a part thereof.

In the drawing—

Fig. 1 is a perspective view of a tote box, showing our new design, the hinged side members being shown disposed on the interior of said tote box;

Fig. 2 is a perspective view thereof, the hinged side members being shown disposed on the exterior of said tote box; and

Fig. 3 is a front elevational view thereof looking from the front of Fig. 1.

We claim:

The ornamental design for a tote box, as shown.

IRVING M. FOOTLIK.
FRANK JOHNSON.
